UNITED STATES PATENT OFFICE.

GEORGE SEKULICH, OF NEW YORK, N. Y.

HAIR CLIPPER.

Application filed August 22, 1927. Serial No. 214,737.

This invention relates to hair clippers, and the primary object of the invention is to provide simple and efficient means whereby the handles can be set at any desired angle with respect to the head of the clipper without the necessity of taking the clipper apart or varying its construction and operation.

A further object is to provide a hair clipper embodying the handle adjustment referred to above, and possessing simple and durable construction as well as being efficient and reliable in operation. Other objects will become apparent as the nature of the invention is better understood, and the same consists in the novel form, combination and arrangement of parts hereinafter more fully described, shown in the accompanying drawings and claimed.

In the drawings, wherein like reference characters indicate corresponding parts throughout the several views,

Figure 1 is a top plan view of a hair clipper constructed in accordance with the present invention;

Figure 2 is a side elevational view thereof;

Figure 3 is a fragmentary bottom plan view of the handle which is adjustably associated with the head member of the clipper;

Figure 4 is an enlarged top plan view of the clipper with the handles removed;

Figure 5 is a horizontal section on line 5—5 of Figure 2;

Figure 6 is a vertical section on line 6—6 of Figure 1;

Figure 7 is a transverse section on line 7—7 of Figure 1; and

Figure 8 is a horizontal section on line 8—8 of Figure 6.

Referring more in detail to the drawings, the present hair clipper comprises an inverted U-shaped head member 5 having a comb plate 6 rigidly secured to the lower ends of the legs thereof by means of stud screws 7 which pass through the comb plate inwardly of the teeth 8 of the latter and are removably threaded in sockets in the lower ends of the legs of the head member 5 whereby the comb plate is removably attached to the latter. Slidably disposed upon the comb plate 6 is the cutter plate 9 having a relatively large rectangular central opening 10 into which the legs of the head member 5 project. As shown clearly in Figure 8,

the legs of the head member 5 engage opposite walls of the opening 10 and are of lesser width than the latter so as to permit the cutter plate to slide back and forth upon the comb plate in a generally well known manner. The cutter plate 9 is yieldingly held in one limit of its movement by means of a helical compression spring 11 which is arranged within the opening 10 of said cutter plate and bears at one end against the latter at one end of the opening 10 and at its other end against a connecting bar 12 provided between the lower ends of the legs of the head member 5.

Journalized in the central horizontal portion of the head member 5 is a vertical shaft or spindle 13 having a ratchet wheel 14 fixed upon the lower end thereof between the cutter plate 9 and the horizontal intermediate portion of the head member 5, and pivotally mounted upon one end of the comb plate 9 is a pawl 15 arranged to engage the teeth of the ratchet wheel 14 so that when the latter is turned in a clockwise direction as seen in Figure 5, the cutter plate 9 will be forced or slid relative to the comb plate against the action of spring 11, thereby effecting a cutting operation by cooperation of the teeth 16 of the cutter plate with the teeth 8 of the comb plate. As shown, the pawl 15 is yieldingly held in engagement with the teeth of the ratchet wheel 14 by means of a suitable wire spring 17 having an end fastened in the adjacent leg of the head member 5. The cutter plate 9 is pressed into frictional engagement with the upper surface of the comb plate 6 by means of a presser plate 18 which is arranged upon the cutter plate 9 and between the legs of the head member 5 beneath the ratchet wheel 14, so as to substantially close the opening 10 of the cutter plate and retain the spring 11 in place. As shown, the resilient presser plate 18 is preferably of transversely curved form and is anchored at one end upon a screw 19 which has a reduced lower end 20 pivotally engaged in an opening 21 in one end of the cutter plate 9, the pawl 15 being threaded onto the screw 19 above the adjacent end of the pressure plate 18 as shown clearly in Figure 7. As the plate 18 is directly beneath the ratchet wheel 14, the screw 19 will be held with its end 20 engaged in the opening 21, and by vertically adjusting the adjacent end of plate 18 and pawl 15 relative to the screw 19, the plate 18 may be

flexed to exert the desired pressure at its other free end upon the cutter plate. Such adjustment of the plate 18 and pawl 15 may be effected by holding these parts against 5 turning and rotating the screw 19, in an obvious manner.

Rotatably mounted upon the shaft or spindle 13 directly above the horizontal intermediate portion of the head member 5 is 10 the hub member 21^a formed upon one end of a stationary handle 22. Provided in the upper surface of the horizontal intermediate portion of the head member 5 is a circular series of radial grooves 23, and carried by 15 the handle 22 is a pivoted spring pressed catch 24 having one end yieldingly projected to engage in a groove 23 to prevent turning of the handle 22 of the clipper relative to the head thereof. The catch 24 preferably 20 has a finger piece 25 exposed at the upper side of the handle 22 and adapted to be pressed for swinging the catch and releasing its lower end from the associated groove 23. Obviously, when the catch 24 is released, the 25 handle 22 may be swung about the shaft 13 to any desired angular position relative to the head of the clipper, and upon releasing the catch 24, it will engage in the registered one of the grooves 23 for holding the handle 30 in its adjusted position. An operating handle 26 has one end fastened upon the upper end of the shaft or spindle 13 so that when the handle 26 is pressed toward the handle 22, the ratchet wheel 14 will be turned in 35 the proper direction for sliding the cutter plate 9 against the action of spring 11 through the medium of pawl 15, the cutter plate 9 returning to its normal position under the action of spring 11 as soon as the 40 handle 26 is released. Obviously, by swinging the handle 26 in a counter-clockwise direction or away from the handle 22, said handle 26 may be adjusted at any desired angular position relative to the head of the 45 clipper, the ratchet wheel 14 freely ratcheting past the pawl 15 at such time. When the handle 26 has been properly adjusted, the corresponding adjustment of the handle 22 may be subsequently effected to obtain the 50 desired relation between the handles as will be apparent. As shown, the shaft 13 has an externally threaded upper end onto which the adjacent end of the handle 26 is threaded, and provided in this upper end of shaft 55 13 is a bore into which is threaded a wedge plug 27 by means of which the threaded upper end of the shaft 13 is expanded to firmly lock the handle 26 to the shaft 13 and likewise secure the nut 28, which is 60 threaded upon the shaft 13 above the handle 26, from turning. The expansion of the upper end of shaft 13 is facilitated by longitudinally slotting the bored portion of the same as at 29. In this way, the handle 26 65 is effectively fastened on the upper end of

the shaft or spindle 13 so as to cause turning of the latter when the handle 26 is actuated, and at the same time the parts may be readily disassembled by removing the plug 27 to free the nut 28 and handle 29 for being threaded off of the shaft 13, the upper end of the latter being reduced so that said shaft may be moved downwardly through the opening in the head member 5 after the comb plate 6 is detached therefrom by removal of the stud screws 7. Naturally, this provides for convenient manufacture and assembly. 70 75

As shown, the cutter head may be reversible by providing opposite edges of the 80 comb and cover plates with teeth, the co-operating teeth at one side of the head being preferably finer than those at the other side and adapted for selective use in accordance with requirements. As the handles are 85 adjustable to any desired angular position completely about the axis defined by spindle 13, any desired angular adjustment of the handle relative to either pair of co-operating cutting edges of the head, may 90 be had. 95

The operation having been dealt with as the description progressed, it is believed that the manner of use as well as the advantages of the invention will be readily appreciated by those skilled in the art. 100

Minor changes may be made without departing from the spirit and scope of the invention as claimed.

What I claim as new is:—

1. In a hair clipper, the combination of 105 a head member having a comb plate secured thereto, a vertical shaft journaled through said head member, a handle rotarily adjustable about said shaft above the head member, a second handle fixed on the shaft above the first handle, a cutter plate slidable on the comb plate, a ratchet wheel fixed on the shaft below the handles, a spring-pressed pawl engaging said ratchet wheel and 110 mounted on the cutter plate to cause sliding of the latter in one direction when the second handle is operated, and a spring to yieldingly slide the cutter plate in the opposite direction. 115

2. In a hair clipper, the combination of 120 a head member having a comb plate secured thereto, a vertical shaft journaled through said head member, a handle rotarily adjustable about said shaft above the head member, a second handle fixed on the shaft above the first handle, a cutter plate slidable on the comb plate, a ratchet wheel fixed on the shaft below the handles, a spring-pressed pawl engaging said ratchet wheel and 125 mounted on the cutter plate to cause sliding of the latter in one direction when the second handle is operated, and a spring to yieldingly slide the cutter plate in the opposite direction, said head member having a 130

circular series of radial grooves in the upper surface thereof, and a spring-pressed catch carried by the first handle for selective engagement in said grooves.

- 5 3. In a hair clipper, the combination of a head member having a comb plate secured thereto, a vertical shaft journaled through said head member, a handle rotarily adjustable about said shaft above the head member, a second handle fixed on the shaft above the first handle, a cutter plate slideable on the comb plate, a ratchet wheel fixed on the shaft below the handles, a spring pressed pawl engaging said ratchet wheel and mounted on the cutter plate to cause sliding of the latter in one direction when the second handle is operated, a spring to yieldingly slide the cutter plate in the opposite direction, said cutter plate having a 10 rectangular opening, said head member embodying an inverted U-shaped member having legs slidably engaging opposite side walls of said opening, and a connecting bar between said legs, said spring being arranged in said opening and bearing at opposite ends respectively against an end wall of said opening and against said connecting bar.

- 25 4. In a hair clipper, the combination of a head member having a comb plate secured thereto, a vertical shaft journaled through said head member, a handle rotarily adjustable about said shaft above the head member, a second handle fixed on the shaft above the first handle, a cutter plate slideable on the comb plate, a ratchet wheel fixed on the shaft below the handles, a spring-pressed pawl engaging said ratchet wheel and mounted on the cutter plate to cause 30 sliding of the latter in one direction when the second handle is operated, a spring to yieldingly slide the cutter plate in the opposite direction, and a presser plate anchored for vertical adjustment at one end on

the cutter plate and engaging the under side 45 of the ratchet wheel at a point between its ends, the other end of said presser plate bearing upon said cutter plate to press the latter against the comb plate.

5. In a hair clipper, the combination of a head member having a comb plate secured thereto, a vertical shaft journaled through said head member, a handle rotarily adjustable about said shaft above the head member, a second handle fixed on the shaft above the first handle, a cutter plate slideable on the comb plate, a ratchet wheel fixed on the shaft below the handles, a spring pressed pawl engaging said ratchet wheel and mounted on the cutter plate to cause sliding 50 of the latter in one direction when the second handle is operated, a spring to yieldingly slide the cutter plate in the opposite direction, said cutter plate having a rectangular opening, said head member embodying 55 an inverted U-shaped member having legs slidably engaging opposite side walls of said opening, a connecting bar between said legs, said spring being arranged in said opening and bearing at opposite ends respectively 60 against an end wall of said opening and against said connecting bar, and a presser plate anchored at one end on the cutter plate and passing between the legs of the head member beneath the ratchet wheel.

6. In a hair clipper, a head member, a comb plate rigid therewith, an apertured cutter plate fitting about the head member and slideable on the comb plate, a vertical shaft journaled in the head member, a ratchet wheel secured on the lower end of said shaft, a pawl engaging the ratchet wheel and mounted on the cutter plate, a handle rotarily adjustable about the shaft above the head member, and a second handle secured on said shaft.

In testimony whereof I affix my signature.
GEORGE SEKULICH.
